TELEVISION SYSTEM

Alfred N. Goldsmith, New York, N. Y., assignor
to Radio Corporation of America, a corporation
of Delaware

Application August 14, 1930, Serial No. 475,188

9 Claims. (Cl. 178—6)

The present invention relates to television systems, and, in particular, to television systems of a type such that it is possible to change from one scene to another without the necessity of interrupting the transmission, and so arranged that the two pictures are mixed or blended during the time when the transmission of one picture is being stopped and the transmission of the other picture is being started. According to motion picture technique, this process has become known as the "fading in" and "fading out" process, or, when these occur simultaneously, as "lap dissolves". It has long been recognized that it is more pleasing to the eye to view a picture where the scene is changed by the gradual disappearance of one scene and the gradual appearance of the other than to change abruptly from one to another scene, either sequentially or concurrently, and it is a principal purpose and object of the present invention to provide ways and means for accomplishing this desirable result.

By the accompanying drawings which form a part of my present disclosure, when read in conjunction with the following specification and claims, I have shown several embodiments of systems adapted and suited to carry out the purposes of this invention, wherein:

Fig. 1 illustrates one form of system wherein the "fading in" and "fading out" is controlled in accordance with the amount of useful energy which may be drawn from a plurality of separate photo cell amplifiers;

Fig. 2 discloses a modification wherein the intensity of the illuminating source for each of the two pictures is controlled;

Fig. 3 discloses a modification of the arrangement shown by Fig. 2 wherein the useful light from each source of illumination which reaches the picture may be controlled;

Fig. 4 still further modifies the construction shown by Fig. 3 and controls the amount of useful light which may reach independent photo cell amplifiers; and,

Fig. 5 illustrates one form of screen suitable for use in connection with the showing of either Fig. 3 or Fig. 4.

According to the present invention, I have provided two independent transmitter assemblages, and have parallelly connected the output of each so that one or the other or both, in varying degrees, each may influence an appropriate amplifying system. According to various modifications, the amount of energy from each of the photo cell amplifiers may be controlled in vari-

ous ways, for example the output strength may be controlled through the use of suitable potentiometers arranged in the output of each of the photo cell amplifiers and so designed and constructed that as the useful output of one is decreased, the useful output of the other is increased, and vice versa. Also, it is possible to construct and arrange the system in such a manner that the illumination upon one of the two subjects is being increased while being decreased on the other, and vice versa, so as to control the current flowing in each of the photo cell amplifiers. A still further means for controlling the "fading in" and "fading out" of two separately transmitted picture subjects may be provided by means of screens arranged either to dim the light from one source while increasing the light from the other, or vice versa, or by dimming or increasing the amount of useful light reaching the photo cell amplifier, so that the current flowing therethrough may be of strength proportionate to both the intensity of light and shadow of the picture, and the degree of illumination of the subject as can affect the photo cell amplifier.

To refer now more particularly to the drawings, I have shown two separate subjects, A and B, which are to be transmitted, so that if it is assumed that the subject A has been transmitted, and it is desired to change the transmission from subject A to subject B, the image produced by subject A may be brilliant, then dim and finally disappear, while the image corresponding to subject B is first invisible, then dim, and then finally appears with maximum brightness at the receiver end of the system. In accordance with this provision, I have provided a source of illumination 1 for illuminating subject A and a separate source of illumination 3 for illuminating subject B. The source 1 preferably comprises an arc formed from electrodes 5 and 7, so arranged that the light issuing therefrom, when the electrodes are connected by means of conductors 9 and 11 with a power source connected to the terminals 21 and 23, will be focused upon the image A. Where desired, suitable lens, mirror, or combined systems may be used, although it is sometimes found that the intensity of the arc source is, of itself, sufficient to properly illuminate the subject. If desired, reflectors 6 of the type shown by Fig. 2 may be used in conjunction with the arc. Similarly, for illuminating subject B by means of the arc 3, I have provided electrodes 13 and 15 similarly connected through conductors 17 and 19 to the terminals 21 and 55

23 of the power source. As shown, these light sources will continually emit light toward the subject, although, where desired, I may provide suitable switches for disconnecting either or 5 both of the arcs from the power line connected at 21 and 23.

In the transmission of the subject A, the subject may be suitably focused by means of a lens 25 (although the lens is not essential) upon a 10 scanning disk 29 capable of rotation upon a shaft 30 in the direction shown by the arrow. The scanning disk 29 may be of the usual Nipkow type provided with either lenses or apertures arranged in a spiral path. As the image of the subject A 15 is focused upon the disk 29, due to the rotation of the disk element, successive elemental areas of the object are caused to influence the photo cell 31 to varying degrees of light and shadow. Through the conductors 33 and 35 this cell is 20 suitably connected with a photo cell amplifier 41. Anode potential for the cell is supplied by means of a battery 37, and as the varying intensities of light and shadow reach the cell, these suitably control the grid potential of the amplifier 41 by 25 reason of the varying potential drops produced in the resistor 39 shunting the amplifier input circuit. The output energy from the amplifier 31 is connected by means of a conductor 43 to one 30 terminal 45 of a potentiometer having a resistance element 47, to the opposite end of which at 49 is connected the plate battery for the amplifier. A suitable control element 51 is rotatably mounted 35 at a point 53, so that as the conductor terminal 87 thereof contacts with various points on the resistance portion 47, varying strength currents will 40 flow in the conductor 55 connected to the center terminal 53 so as to pass through the primary winding 57 of the transformer 59. The secondary 45 61 of the transformer 59 is appropriately connected with a modulator which is so arranged that it 50 may appropriately modulate a suitable carrier frequency for transmission of the picture point energy either by radio or wire line.

Similar to the arrangement shown in connection 45 with the transmission of the image A, I may provide a lens 27 for focusing the image B upon the disk 63 which is arranged to rotate about the shaft 65 in the direction shown by the arrow. Light values proportionate to the intensity of light 50 and shadow upon each elemental area of the image 13 are fed through suitable conductors 69 and 71 to the input circuit of the amplifier 77. The photo cell 67 is provided, similarly to the cell 31, with a suitable source of anode potential, and across 55 the input circuit of the amplifier 77 is connected a resistor 75, similar to that shown at 39 in connection with the amplifier 41. The output of the amplifier 77 is connected through the conductor 79 to a terminal 81 of a second potentiometer including a resistance element 82 having its opposite end 83 connected to the plate energy supply 60 source for the amplifier 77. The terminals 83 of the resistance element 82 and 49 of the resistance element 47 are connected in the usual manner, so that there will be a return circuit for the primary 57 of the transformer 59 to either amplifier 41 or 77. As the conductor member 51 is rotated in either clockwise or counter-clockwise direction, depending upon whether it is desired to 65 cause the picture subject A to gradually disappear and picture subject B to gradually appear, or vice versa, the current flowing from either amplifier 41 or 77 passes through a greater or lesser portion 70 of the resistances 47 and 82. Thus, with the con-

ductor element 51 in the position shown, and assuming the contact arm 51 to be moving counter-clockwise, so that it makes contact at 87 with resistance 47, and at 89 with resistance 82, it will be observed that picture subject A has substantially disappeared, while picture subject B has influenced the modulator and transmitter to approximate the maximum extent. It is, of course, apparent that the maximum influence of each of the photo cells 31 and 67 and their amplifiers 41 and 77 in the direction shown will be determined by a further counter-clockwise rotation of the conductor member 51, so that the ends 87 and 89 thereof respectively are at the points 49 and 81 respectively. In this case, picture A will have 15 completely disappeared and picture B will be the picture being transmitted. If it is desired to later change the transmission from picture B to picture A, the potentiometer conductor element 51 is then rotated in a clockwise direction and picture B 20 disappears while picture A appears.

It is, of course, recognized that this arrangement may, to some extent, affect the frequency characteristics of the system. However, to overcome this difficulty any suitable and well known 25 form of mixer may be used as a compensator for the change in frequency.

Now referring to Fig. 2, I have provided a similar arrangement to that shown in connection with Fig. 1 for illuminating each of the picture subjects A and B, and this is preferably provided by means of intense sources of light 2 and 4 which are focused by means of reflectors 6 and 8 upon the picture subjects A and B respectively. As was shown by Fig. 1, the photo cells 31 and 67, responsive to either pictures A or B, are connected through suitable amplifiers 41 and 77. However, as shown by Fig. 2, the effective current strength from the two amplifiers 41 and 77 is not controlled, and the outputs thereof are suitably connected through the same conductors 43 and 79 to the primary winding 57 of the transformer 59, whose secondary element 61 is connected with the modulator and transmitter in the manner described in connection with Fig. 1. In the present instance, in order to suitably control the transmitter, and to determine which of picture subjects A and B is to be transmitted, and to control the varying strength of transmission dependent upon each of the subjects, I have provided in the supply line to the light sources 2 and 4 suitable rheostats 91 and 93 controlled from a common control element rotatably mounted at 95. As shown, it will be observed that the source 4 is more intense than the source 2, and, therefore, the strength of picture subject B as transmitted is greater than picture subject A. Now, if it is desired to cause picture subject A to disappear completely, the control element of the rheostats 91 and 93 will be still further rotated in a counter-clockwise direction, so that there is a maximum amount of resistance in series with the conductor 9 connecting the source 2 with the power line terminals 21 and 23, and a minimum amount of resistance in the line 17 connecting the source 4 with the terminal 21 which is connected to the power line. It is thus observed that this likewise provides a most convenient arrangement for causing one picture subject to fade out while the other 70 fades in.

According to the showing in Figs. 3 and 4, I have still further modified the arrangement by providing a system wherein it is neither necessary to control the intensity of the illumination nor the 75

output of the photo cell amplifier directly. This has been provided by means of a rotatable disk element of the type shown by Fig. 5. This disk is so arranged that at one portion thereof it is completely black, and then tracing the figure in a counter-clockwise direction, this black gradually fades into a dark gray, then to a middle gray, then to a light gray, and finally to a plain white. It is, therefore, observed that in one position the disk 97 or 99 will completely block all light which reaches the same, while in a position substantially 360° therefrom substantially all of the light reaching the disk passes therethrough, and for intermediate pulses the amount of light passing through the disk is suitably varied.

In accordance with the showing of Fig. 3, I have provided an arrangement such that there is a disk 97 placed in front of the light source 1, and a disk 99 placed in front of the light source 20 3, so as to control the amount of light from each of these sources which reach the picture subject A or B. The disk 97 is arranged to rotate about the shaft 101, while the disk 99 is arranged to rotate about the shaft 103. When the disks 25 are constructed in accordance with the showing of Fig. 5, it is, of course, desirable to have them arranged such that they may be moved by means of a common element such as a connection shown in dotted lines at 105. With such an arrangement, as one disk is changed from white to black, the other disk changes from black to white. Thus, in order to provide a means such that light reaching picture A is gradually decreased, while the light reaching picture B is gradually increased, one disk 97 is arranged to rotate in a 30 clockwise direction while the disk 99 is arranged to rotate in a counter-clockwise direction, whereas if the intensity of picture B were being decreased while that of picture A was being increased, the disk 97 would be rotated counter-clockwise and the disk 99 clockwise. This may be provided most conveniently by means of any suitable gearing and any suitable control therefor.

45 Instead of the disk mechanism of Figs. 3 and 4 for producing the fade in and fade out, where desired, I may substitute any well known form of dissolving diaphragm or shutter as is known from motion picture technique.

50 Now making reference to Fig. 4, the arrangement disclosed therein is substantially a duplication of that shown by Fig. 3 with the exception that the disks 97 and 99 carried by the shafts 101 and 103 are arranged to rotate directly in front of the photo cells 31 and 67 so that they permit a greater or lesser amount of light from the picture subject A or B to influence either or both of the cells.

60 While the invention has hereinabove been described particularly in connection with scanning elements of the Nipkow disk type, it is, of course, obvious that the invention is not limited to the specific structure shown, since it falls clearly 65 within the spirit and scope of the present invention to substitute for the Nipkow spiral disks any other known type of scanning elements, such as the Braun tube used for transmission, mirror disks arranged to suitably rotate and scan a picture subject, rotating tapes, drum disks or oscillating mirrors, or, in fact, any and all known types of transmission systems. It is, therefore, to be regarded that I have merely for convenience of illustration shown a scanning element as comprising a disk rather than to illustrate it by any

other form. However, I believe myself to be entitled to use any form of scanning element which is to be found suitable, and may, therefore, replace the scanning disk by any of the above named types of scanning elements.

5 Many other modifications not herein shown or described may at once suggest themselves to those skilled in the art to which the invention relates, and I believe myself to be entitled to make and use any and all of these modifications provided, 10 of course, they fall fairly within the spirit and scope of the present invention as has been herein-after set forth by the appended claims.

Having now described my invention, what I claim and desire to secure by Letters Patent is 15 the following:

1. In a system for transmitting images, the method of changing the transmission from one image representation to a different image representation which includes the steps of projecting 20 a plurality of light images upon scanning devices, dividing the images into a plurality of independent elemental areas to cause the production of image signals representative of each, and decreasing the intensity of one signal while increasing the intensity of the other signal during the period of transition to cause the prior image to fade-out and the subsequent image to fade-in at points of reception.

2. In a system for transmitting images, the 30 method of changing the transmission from one image representation to a different image representation which includes the steps of projecting a plurality of light images upon scanning devices, dividing the images into a plurality of independent elemental areas to cause the production of image signals representative of each, and modifying the intensity of each light image during the transition period to cause one signal output to increase and the other signal output to decrease.

3. In a system for transmitting images, the method of changing the transmission from one image representation to a different image representation which includes the steps of projecting 45 a plurality of light images upon scanning devices, dividing the images into a plurality of independent elemental areas to cause the production of image signals representative of each, and varying the intensity of the signals produced from each image 50 during the transition period so that one signal intensity increases and the other signal intensity decreases.

4. In a system for transmitting images, the method of changing the transmission from one 55 image representation to a different image representation which includes the steps of illuminating each of a plurality of subjects of which the image representation is to be produced, projecting light representative of the light values on each 60 subject upon scanning devices, dividing the images into a plurality of independent elemental areas to cause the production of image signals representative of each, and changing in inverse order the intensity of the light illuminating each subject 65 so as to produce resulting image signals of increasing magnitude to represent one subject and the production of signals of decreasing magnitude to represent the other subject during the transition period.

5. In a system for producing electro-optical representations of subjects located at a point of transmission and for changing the transmission from one to another of a plurality of different subjects, a plurality of scanning devices for ana- 70 75

lyzing each of a pair of light images representative of the subject during the period of changing from one to the other so that the light images are divided during the analyzing period into a plurality of elemental areas to cause the production of signal output from the system, means co-operatively associated with each scanning device to convert the light values into electric current impulses, and means co-operating with said analyzing systems and interlocked with each for producing a decrease in the intensity of the useful output current from one system and an increase in the intensity of the useful output current of the other systems to cause one image representation to fade-out and the other image representation to fade-in.

6. In an electro-optical system for producing fade-in and fade-out of images during the changing of one image transmission to a different image transmission, a plurality of scanning systems for converting the intensity of light and shadow of elemental areas at each of the images into proportional strength electric current impulses by dividing each of the images into a plurality of elemental areas, and scanning the elemental areas according to a pre-established scanning pattern, and means co-operating with each of the scanning systems and interlocked with each other for controlling the strength of the current output therefrom so that the current impulses produced by one system decrease in intensity with an increase in the current impulses from the other system during the transition period.

7. In an electro-optical image producing system for producing fade-in and fade-outs of images during the change from one image transmission to a different image transmission, a plurality of light sources for illuminating each of a plurality of subjects of which the electro-optical image representation is to be produced, a plurality of scanning systems subjected to the light values of each of the plurality of subjects, said scanning systems being arranged so as to analyze each of the light images by dividing each image into a plurality of elemental areas which are scanned according to a pre-established pattern of scan-

ning to cause the production of electric signal impulses of magnitude proportional to the light brilliance of the several elemental areas, a combined output circuit for the scanning systems and interlocked means for decreasing the light intensity falling upon one of the subjects of which the electro-optical image representation is to be produced and for increasing the light brilliance falling upon the other subject of which the electro-optical image representation is to be produced so that during the transition period the resulting current impulses representative of each of the subjects causes the fade-in and fade-outs of the electro-optical representations produced at suitable receiving points.

8. In a system for transmitting images, the method of changing the transmission between one predominating image representation and a different predominating image representation which includes the steps of projecting a plurality of light images upon scanning devices, dividing the images into a plurality of independent elemental areas to cause the production of image signals representative of each, varying the intensity of the signals produced from each image during the transition period so that one signal intensity increases to a predetermined level and the other signal intensity decreases to a predetermined intensity level and subsequently transmitting the predominating image in conventional manner.

9. In a system for transmitting images, the method of changing the transmission between one predominating image representation of a subject and a different predominating image representation of a different subject which includes the steps of projecting the plurality of light images of the subjects upon scanning devices, dividing the images into a plurality of independent elemental areas to cause the production of image signals representative of each, and varying the intensity of the signals produced from each image during the transition period so that one signal intensity increases to a predetermined level and the other signal intensity decreases to a predetermined intensity level.

ALFRED N. GOLDSMITH.
